UNITED STATES PATENT OFFICE.

ASHER MERWIN AND C. H. HOBART, OF PADUA, ILLINOIS.

IMPROVEMENT IN CORN-PLANTERS.

Specification forming part of Letters Patent No. 40,492, dated November 3, 1863.

To all whom it may concern:

Be it known that we, A. MERWIN and C. H. HOBART, of Padua, in the county of McLean and State of Illinois, have invented a new and Improved Corn-Planter; and we do hereby declare that the following is a full, clear, and exact description of the same, reference being had to the accompanying drawings, making a part of this specification, in which—

Figure 1 is a side sectional view of our invention, taken in the line *x x*, Fig. 2; Fig. 2, a plan or top view of the same; Fig. 3, a section of a portion of the same, taken in the line *y y*, Fig. 1.

Similar letters of reference indicate corresponding parts in the several figures.

To enable those skilled in the art to fully understand and construct our invention, we will proceed to describe it.

A represents a rectangular frame, which is formed of longitudinal bars *a*, connected at their ends by cross-bars *b*.

B is a driver's seat, which is secured to supports *c* in the frame A, and C is an axle, which is attached to the frame A at about its center. The wheels D' D' are at the inner sides of the outer bars, *a*, of the frame A, as shown in Fig. 2.

To the front part of the frame A there are attached a series of vertical bars, *d*, which are in a plane parallel with the axle C. Two of these bars *d* are rather longer than the others, and to the lower ends of said bars there is pivoted, at *a'* *a*, frame, D, to which two seed-hoppers, E E, are attached, and two furrow-shares, F F. The seed-hoppers have a slide, G, passing through them, which is perforated at its ends and serves as a seed-distributer, the slide being operated by means of a lever, H, which passes up through the frame A, just in front of a seat, I, on the frame A. This seed-distributing slide is arranged to operate in the usual way, and therefore does not require a particular description.

The frame D is connected by a toggle, J, to the under side of the draft-pole K of the machine, and this toggle J is connected at its joint by a rod, L, with a lever, M, the latter

extending up through the back part of the frame A, by the side of the driver's seat B. By operating the lever M the frame D may be raised and lowered through the medium of the toggle J. The frame D is elevated in order to raise the furrow-shares F F above the surface of the ground—as, for instance, in turning the machine at the ends of rows or in drawing it from place to place. The lever M may be secured in position by a spring-catch, N, which may be actuated so as to relieve said lever, when necessary, by the foot of the driver.

O represents parallel bars, the front ends of which are secured by pivots *e* to the lower parts of the bars *d*. These parallel bars form two frames, O' O', of three bars each, the bars of each frame being connected at their back parts by cross-bars *f f*, through which and the bars O bolts *g* pass. Several holes may be made in the cross-bars *f f* for the bolts *g* to pass through, in order to admit of the bars O being adjusted nearer together or farther apart, as may be desired. (See Fig. 2.) Each bar O has an inclined foot or standard, P, attached to it, and to these standards plows Q are secured.

To the back end of the central bar, O, of each frame O' there is attached a bar, R, and these bars R have levers S connected to their upper ends, said levers having their fulcra at *h* on the frame A. These levers S may be operated by the driver with his feet, so that the plows may be elevated above the ground when necessary.

Having thus described our invention, what we claim as new, and desire to secure by Letters Patent, is—

The frame D, pivoted to vertical bars *d*, attached to the front part of the frame A of the machine, when said frame is arranged with or raised and lowered by means of the toggle J, rod L, and lever M, substantially as herein set forth.

ASHER MERWIN.
C. H. HOBART.
